(57) **CLAIM**

The ornamental design for a can opener, as shown and described.

DESCRIPTION

FIG. 1 is a top perspective view of a can opener design showing my new design.

FIG. 2 is a front view of a can opener.

FIG. 3 is a rear view of a can opener.

FIG. 4 is a left side view of a can opener.

FIG. 5 is a right side view of a can opener.

FIG. 6 is a top view of a can opener.

FIG. 7 is a bottom view of a can opener.

FIG. 8 is a bottom perspective view of a can opener; and, FIG. 9 is a top perspective view thereof, showing the can opener in a folded state of use.

The broken lines depict portions of the can opener that form no part of the claimed design.
